UNITED STATES PATENT OFFICE.

CLARENCE N. FREY, OF CINCINNATI, OHIO.

SELF-LOCKING RECEPTACLE.

1,155,719.

Specification of Letters Patent.

Patented Oct. 5, 1915.

Application filed January 8, 1912. Serial No. 670,082.

To all whom it may concern:

Be it known that I, CLARENCE N. FREY, a citizen of the United States, residing at Cincinnati, in the county of Hamilton and State of Ohio, have invented certain new and useful Improvements in Self-Locking Receptacles, of which the following is a specification.

My invention relates to self-locking receptacles, and has for its object the provision of a receptacle with means whereby the insertion of the goods will place locking means therefor in locking relation, so that, when the lid of the receptacle is closed, the same is automatically locked.

My invention is applicable to receptacles into which goods are arranged to be delivered, and is illustrated as a receptacle for receiving milk containers.

The invention will be readily understood from the foregoing, and from the following description and claim, and from the drawing, in which latter:

Figure 1 is a plan view of my improved device, with the lid partly broken away, and the milk-bottles shown in the outside cage. Fig. 2 is an end elevation of the case, the casing being shown in section on the line 2—2 of Fig. 3. Fig. 3 is a vertical cross-section of my improved device, taken on a line corresponding to the line 3—3 of Fig. 2, showing the parts in unlocked relation. Fig. 4 is a similar view of the same, with one end of the same broken away, and the parts in locked relation; and, Fig. 5 is a side elevation of the key of my improved device.

11 represents the casing, which may be of suitable form to receive the articles for which the same is intended, and may be in one compartment, or divided into a plurality of compartments. I have shown the same divided into a plurality of compartments 12, by partitions 13.

14 is a lid hinged to the casing by hinges 15. My invention contemplates the employment of one or more locks. I have shown two locks 16 employed. When more than one lock is employed, I prefer to interconnect the same, so that when goods are received in the receptacle at any portion thereof, all the locks will be placed in locking relation for locking the cover firmly in place when the cover is closed. In the exemplification of my invention which I have preferred to show, the lock comprises a bolt 17 shown on a lever 18, shown as a bell-crank

lever, pivoted at 19 to the casing and arranged to coöperate with a keeper 20 on the lid. The bolt is normally held out of operative relation with the keeper, which in the present instance is accomplished by gravity, the lever normally resting against a pin 21. 24 is a lever pivoted at 25 to the casing. 26 is a link articulated with the levers 18 and 24 by articulations 27 and 28. 30 is a stirrup pivoted on a pin 31 on a bracket 32 secured to the casing at one end of the stirrup. The other end of the stirrup has connection with the lever 24, as by means of a bracket-piece 33, articulated to the stirrup 30 by a pin 34 and to the lever 24 by a pin 35. 36 is a metal strap secured to the casing and is preferably located a slight distance above the bottom 37 of the casing, the strap having a recess 38 therein for receiving the stirrup 30, so that when the stirrup is received in the recess the upper faces of the strap and stirrup are substantially level for supporting the package, shown as a bottle 39 for milk, cream, or the like, in upright position. If more than one compartment or more than one locking means is employed for the receptacle, a stringer 43 is employed which is received crosswise of the compartments under the partitions and articulated as shown by the articulations 44 to the stirrups. The metal straps 36 maintain the stirrups and stringer off the bottom 37 of the casing for preventing indentations of the outer bottom wall of the casing during use, and preventing injury to the packages contained in the casing by blows upon said outer bottom, and thereby enable a casing of light metal to be employed. The straps, stirrups and stringer provide narrow supports for the packages, whereby a low cost of production is assured, and ventilation under the packages is obtained. The articulations between the stirrups and stringer, and for mounting the stirrups, further provide ready and cheap means for assembling the parts. I have, as stated, shown two of these locking mechanisms, the elements of which are designated by similar reference numerals, the locking mechanisms being shown as duplicates of each other. I have shown an intermediate compartment not provided with a lock, although the same is provided with a stirrup 30' articulated to the stringer 43 by a pin 44' for acting on the locks in the end compartments.

When the article or bottle is placed in the receptacle the weight thereof will depress the stirrup or stirrups and bring the bolts of the locks into locking position, so that, when 5 the lid of the receptacle is closed, its keepers will cause the bolts to retract and snap back into locking relation with the keeper, for locking the lid. In order to prevent shifting of the lid with relation to the casing, it may be provided with a flange 46 received inside the upper edge of the casing. If it is desired to remove the article from the receptacle, a key, shown at 47 is inserted through a slot 48 in the casing until 10 a recess 49 in the shank of said key registers with the wall of said slot, when the inner or releasing end 50 of the key will be under the stirrup for raising the same and placing the bolt or bolts in unlocking relation, the registry of the recess with the wall of the slot permitting turning of the key. Upon removal of the article, the bolts will again be maintained in unlocking relation. Each end wall of the casing may be provided with a 15 slot 48.

53 is a basket secured to the outer face of the casing and arranged to receive the empty bottles.

Illustrating the application of my improved device to milk-bottles, the empty milk-bottles are arranged to be placed in the basket as shown in Figs. 1 and 2. The lid or cover, while it may be in downward position, is, in the absence of the article in the casing, in unlocked relation. When the milk is delivered, the filled bottle or bottles are placed in the receptacle, thereby placing the keepers of the locks in locking relation by reason of the weight of the filled bottles 30 resting on the stirrup or stirrups or the stringer between the stirrups. As soon as a bottle is placed in the receptacle, the bolts 35 will be thrown into locking position, so that, when the lid or cover is closed, the same 40 will be automatically locked, preventing 45 tampering with, or theft of, the containers

or their contents in the receptacle. This relation of parts is illustrated in Fig. 3. The employment of the key will permit ready access to the interior of the receptacle by the 50 householder.

The receptacle is arranged to be fastened to a wall indicated at 54 by means of suitable screws 55 whose heads are located inside the receptacle. 55

My improved device is preferably constructed of sheet metal throughout and forms an economical, rigid, and safe receptacle in which the goods may be placed and locked without the employment of a key by 60 the one delivering the goods.

Having thus fully described my invention, what I claim as new and desire to secure by Letters Patent, is:

In a self-locking receptacle, the combination of a casing having an outer bottom wall, a lid for said casing, straps extending next adjacent to but spaced from said outer bottom wall and located inside said casing, stirrups loosely pivoted at one of their ends in 70 said casing and extending across said straps and arranged to be depressed into the plane of said straps, a lever in said casing pivoted to the wall of said casing adjacent to the bottom of the casing, one end of said lever 75 having connection with one of said stirrups for being actuated thereby, a keeper on said lid, a second lever in said casing pivoted to the wall of said casing adjacent to the top of said casing, one end of said last-named 80 lever formed as a bolt coacting with said keeper, and an upright link articulated with the other ends of both said levers, and constructed and arranged for normally retracting said bolt from said keeper. 85

In testimony whereof, I have hereunto signed my name in the presence of two subscribing witnesses.

CLARENCE N. FREY.
